UNITED STATES PATENT OFFICE.

HENRI LOUIS LE BLANC AND HECTOR BEAUDOIN, OF EAST ANGUS, QUEBEC, CANADA,
ASSIGNORS OF ONE-THIRD TO ERNEST LEON LESSARD, OF DISRAELI, QUEBEC,
CANADA.

SIGNAL DEVICE FOR AUTOMOBILES.

Application filed June 18, 1923. Serial No. 646,216.

The present invention relates to signal devices for automobiles, and more particularly to devices of the type in which an arrow or the like is provided which is movable to various positions to indicate the direction in which the car or other vehicle is about to travel.

The invention resides primarily in the provision of improved means or mechanism for effecting the adjustment of the arrow or other indicator to one or another of its several positions, and for locking said indicator in such position and thereafter releasing it when a new change in direction is about to be made, all as hereinafter fully described.

An embodiment of the invention is illustrated in the accompanying drawings, in which:—

Figure 1 is a side elevation of an automobile equipped with a device according to the invention.

Figure 2 is an enlarged diagrammatic view of the signal device and controlling mechanism.

Figure 3 is a sectional view through the casing, of a modified form of the signal operating mechanism.

Figure 4 is a side elevation of the modified form of the controlling mechanism, the casing having been removed.

Figure 5 is a diagrammatic view of the signal controlling mechanism, showing same in its upward vertical position, or in position No. 1.

Figure 6 is a diagrammatic view of the signal controlling mechanism, showing same in its left horizontal position, or in position No. 2.

Figure 7 is a diagrammatic view of the signal controlling mechanism, showing same in its downward vertical position, or in position No. 3.

Figure 8 is a diagrammatic view of the signal controlling mechanism, showing same in its right horizontal position, or position No. 4.

Figure 9 is a diagrammatic view of the signal operating mechanism, here illustrated in position No. 1.

Like numerals of reference indicate corresponding parts in each figure.

Referring to the drawings:—

1 is the base plate of the control member preferably mounted on or adjacent the dashboard of an automobile, and provided ad-

jacent its periphery with a plurality of contacts 2 interconnected by means of the electrical conductors 3, and 4 is a battery connected at one side to said electrical conductors 3 by means of the electrical connection 5 and suitably grounded at 6 at its other side. 55 Located intermediate of said control member 1 is a ratchet 7, the number of teeth on said gear being equal to the number of contacts and 8 is a check pawl adapted to engage said ratchet. On said ratchet is pivotally mounted the contact arm 9 which at its outer end is adapted to engage with said contacts 2, said arm 9 being electrically connected to the magnets 10 by means of the electrical conductor 11 at its inner end. The magnets 70 10 are preferably mounted on the base 12, and located within a casing 13 (see Figure 1) the said casing 13 being preferably secured on the hood or radiator of an automobile or in the rear, as the case may be. The magnets 75 10 are grounded at 113, and 14 is an armature lever pivotally mounted at 15 at one end and carrying at its other end the pawl 16, said pawl co-acting with the ratchet 17 mounted on the shaft 18, on which shaft is 80 also mounted the indicating arrow 19. A spiral spring 20 normally presses pawl 16 against said ratchet 17, and 21 is a spiral spring which tends to move the armature 14 away from the magnets 10. The number of 85 teeth on the ratchet 17 should preferably be equal in number to the teeth on the ratchet 7, so that when a circuit is made through the medium of the contact arm 9 with one of the contacts 2 and the magnets 10, the ratchet 17 will be turned an equal number of steps. 90

In Figures 3, 4, 5, 6, 7, 8 and 9 of the drawings, a modified form of more elaborate construction is disclosed to operate the indicating arrow. 95

In this modified construction of the invention, the controlling element 22 consists of two uprights 23 suitably distanced from one another and connected by the cross bar 24, on which latter are mounted at suitable intervals the contact fingers 25. 100

Above said cross bar 24 is mounted a revolving drum 26, which is provided with a plurality of contacts 27, said contacts being adapted to engage with the fingers 25 so as 105 to move the indicating arrow into different positions, as disclosed in the diagrammatic Figures 5, 6, 7 and 8. The drum 26 is pref-

erably mounted on the shaft 28, which is mounted in the uprights 23. On one end of said shaft 28, is preferably mounted the sleeve 29 which is preferably slideable on said shaft 28 and keyed thereto, and on one end of this sleeve is mounted the elongated handle 30, and on the other end the contact disk-shaped member 31. The said contact member 31 is normally held away from the drum 26 by means of the spiral spring 32 interposed between said drum and said member 31. To operate said contact member 31, the handle 31 is preferably pushed into the position indicated in dotted lines in Figure 3, thus carrying the said member 31 into engagement with the contact members 33 which are located on either side of said drum 26, one of said contact members 33 being connected to the battery 34 (see Figures 5, 6, 7, 8) by means of the electrical conductor 35, while the other contact member 33 is connected to the contact member 36 (see Figures 5, 6, 7, 8).

The above described control member 22 is preferably located on or adjacent the dashboard of the automobile, and the motor 37 operating the directing arrow is preferably located on the hood, radiator, or in the rear of the automobile, as found most suitable.

The motor 37 is preferably mounted within the casing 38, and 39 is a shaft centrally journaled in said casing, and upon which is mounted the armature 40. The armature 40 is preferably connected to the central finger 25 by means of the electrical conductor marked "A", said conductor first entering the compartment 41 located at one end of said casing 38, in which is mounted the coil 42 to which said electrical conductor "A" is connected, the said electrical conductor connecting the brush holder 43, upon which is mounted the brush 44 which contacts with the armature mounted on the shaft 39.

The field coils 45 (see Figure 9) are suitably electrically connected in series by the electrical conductors 1, 2, 3, and 4 respectively. Each of said conductors is connected respectively to one of the fingers 25 located in the controlling mechanism 22. Thus when one of the contacts 27 is brought into position to bridge one of the contact fingers 25 and the contact member 36, by means of the handle 30, a circuit will be closed that will revolve the shaft 39 into the position disclosed in the corresponding one of the diagrammatic Figures 5, 6, 7 and 8.

When the circuit is broken, the coil or magnet 42 is de-energized, and the friction plate or member 46 which is located within the compartment 41 and forms the armature of the coil, is released, and the pins 47 carried by the said member 46 will be pushed out by means of the spiral springs 48 from the holes 49 provided in the partition 50. The friction plate 46 preferably co-acts with

the plate 51 (which is preferably of less conductive material) rigidly mounted on the shaft 39, said plate 51 having a plurality of lugs 52 engaging corresponding recesses 53 in the plate 46. Hence, when the circuit is broken, the lugs 52 will be made to engage the recesses 53 to rigidly hold the shaft 39 in position. When the circuit is again closed, the plate 46 will immediately be carried inwardly by the magnet 42, thus freeing the lugs 52 and unlocking the shaft 39.

On one end of the shaft 39 is mounted a collar 54, carrying a socket 55 in which may be inserted an electric bulb 56 which contacts with the outer end of said shaft 39, and 57 is a brush contacting with said socket 55 and suitably mounted in the brush holder 58, said brush holder being suitably connected to a battery (not disclosed in the drawings) by means of the electrical conductor 59. On the socket 55 is mounted the indicating arrow 60 which revolves with said socket 55, the collar 54 and shaft 39.

What we claim as our invention is:—

1. A direction-signal mechanism comprising a casing, a shaft journaled for rotary movement therein, a compartment at one end of the casing, the outer wall of which is carried by the shaft, an indicator exterior of the other end of the casing and connected to rotate with the shaft, a motor within the casing for rotating said shaft to move the indicator into any selected one of a plurality of different predetermined positions, and a lock operating automatically to hold said shaft against operation while the motor is stationary and to release it when the motor is started, said lock embodying an electromagnet arranged concentrically of the shaft and connected with the motor, studs on the inner surface of the outer wall of the compartment, and a metallic plate yieldingly mounted in the compartment and having recesses normally engaging the studs but adapted to be attracted by the magnet when the magnet is energized to release the shaft.

2. A direction signal mechanism as claimed in claim 1, wherein an annular pocket is provided in spaced concentric relation about the shaft on the end wall of the casing so as to project into the compartment for accommodating the magnet, pins extending from the metallic plate and slideably mounted in the casing for guiding and supporting the plate, and springs arranged about the pins and tensioned to normally hold the plate in engagement with the outer wall of the compartment but adapted to be compressed when the magnet is energized to release the shaft.

Signed at Montreal, Quebec, Canada, this 19th day of May, 1923.

HENRI LOUIS LE BLANC.
HECTOR BEAUDOIN.
